FASTENING STRIP

Louis M. Rabinowitz, Brooklyn, N. Y.

Application July 8, 1943, Serial No. 493,954

5 Claims. (Cl. 24—206)

This invention relates to fastening devices for garments and other articles, and more particularly to adjustable fastening devices of this character comprising a member provided with means adapted to selectively engage and hold in different positions cooperating means carried by a second member, to provide for a ready adjustment of the garment according to the dimension of the parts to which it is to be applied.

Garments, particularly women's garments, have often to be provided with fastening means that, besides supporting the garment on the wearer and offering sufficient resistance to the strains to which the garment is subjected in use, must permit the necessary form-fitting adjustments in the quickest and simplest manner. The fastening means commonly adopted for this purpose comprise, for instance, a series of conventional metal eyes secured to one end of a garment and cooperating with hooks carried by the other end of the garment, or snap-fastener arrangements, slide buckles and similar devices. Their shortcomings are well known, among others, the relative insecurity of the fastening under certain conditions, and the somewhat insecure connection of the metal parts to the garment.

To eliminate these disadvantages, and to reduce the number of metal parts required, it has been proposed to provide adjustable straps made entirely of fabric and embodying surfaces, obtained for instance through the formation of pockets in the strap, adapted to cooperate with conventional hooks, said hooks remaining interlocked with the coacting surfaces after having been guided into engagement therewith, and being easily disengageable therefrom by means of a reverse relative movement of the hooks and of the surfaces-carrying member.

It is the general object of this invention to provide an improved adjustable garment strap of this general character, such a strap having a maximum resistivity to strains and therefore particularly adapted whenever the conditions of use are such as to impose relatively severe strains on the fastening members, or whenever a particularly secure fastening is desired for any other reason. Accordingly, it is an object of the invention to provide a strap having a plurality of series of pockets for engagement with a plurality of cooperating hooks.

A further object of this invention is to provide a strap of this character that can be manufactured in a simple and inexpensive manner, in particular to provide for the concurrent formation of a plurality of series of transversely spaced

pockets with a minimum of material and operations.

These and other objects of the invention will become apparent as the description proceeds.

5 While my invention is advantageously applicable to straps for women's garments, in particular, as mentioned, it is obviously also capable of application to adjustable fasteners for a wide variety of uses, and it will be understood that all such possible applications are within the scope of the invention.

In the drawing:

Figure 1 is a plan view of one embodiment of my strap in a preliminary stage of construction 15 thereof, showing parts that cooperate to the formation of the completed device.

Figure 1a is an end elevation in cross-section on line 1a—1a of Figure 1.

Figure 2 is a side view of the same parts shown 20 in Figure 1.

Figure 3 is a plan view of the device in a more advanced stage of construction.

Figure 3a is an end elevation in cross-section on line 3a—3a of Figure 3.

25 Figure 4 is a plan view of the strap after it has been completed.

Figure 4a is an end elevation in cross-section on line 4a—4a of Figure 4.

Figure 5 is a front view of the strap and of a 30 cooperating member carrying hooks for engagement in the pockets of the strap.

Figures 5a, 5b and 6 are fragmentary plan views of a further embodiment of my strap wherein the transverse spaced pockets are developed from 35 and along a single folding element of my strap. Fig. 6a is an end elevation in section, on line 6a—6a of Fig. 5, and Figs. 6b and 6c are similar end elevations in section on line 6b—6b of Fig. 5b and line 6c—6c of Fig. 6, respectively.

40 Referring now in detail to the drawing, it will be seen that the strap comprises a base strip 10 of any suitable fabric; two parallel narrower strips 11 and 12 made of any suitable fabric, for instance the same fabric used for the base strip, 45 are superimposed on 10 in spaced relation to the side edges thereof, each of said strips 11, 12 being folded transversely upon itself throughout its length at equidistantly spaced intervals, as shown at 13 and 14, to form a series of folds or 50 pleats. Line 13 indicates the outer edge of the folds, dotted line 14 the inner edge thereof, and portion 15 comprised therebetween is the resulting infold which is capable of receiving a hook after completion of the pockets. Obviously, the length of the strap is connected with the num-

ber and size of the folds, these, in turn, being dependent upon the range of adjustment desired and the dimension of the hooks to be used.

The fold-embodying strips 11, 12 are secured in a pleated condition to base strip 10 by means of lines of stitching, as shown at 16 and 17. As in completing the formation of the pockets, in the manner that will now be described, the side edges of marginal portions 18, 19 of base strip 10 are folded over and are caused to overlap upon a portion of the folds of said strips 11, 12, these latter strips must be located on base strip 10 in such a position as to allow for this overlapping.

After strips 11, 12 have been secured to base strip 10, the longitudinal edges 18, 19 of the latter are oppositely inturned and caused to overlap upon a portion of the folds of strips 11, 12, edge 18 being caused to overlap strip 11 and edge 19 strip 12, and are stitched to said strips and the underlying body of strip 10 respectively along lines 20, 21, as shown in Figure 3, the marginal portions of said edges 18, 19 having been previously turned under to form hems 22, 23 as shown in Figure 3a. As it will be readily understood, lines of stitching 20, 21 while anchoring the overlapped edges of base strip 10 to strips 11, 12 and to the underlying surface of strip 10, primarily serve to define one of the sides of the pockets, namely the outer side thereof, and concurrently also add to the strength of the connection of strips 11, 12 with the base strip, connection previously effected by means of lines of stitching 16, 17 parallel to lines 20, 21. These latter lines may be parallel lines 16, 17 more or less closely but obviously should not be spaced outwardly of said lines.

As the base of the pockets is formed by the inner edge 14 of the infold portion of each pocket, and the outer edge 13 is a free edge defining the mouth of the pockets in cooperation with the underlying surface, it is apparent that the construction of the pockets will be completed when the remaining or inner side of the pockets has been defined.

To allow of the concurrent formation of this inner side of the pockets of both strips 11 and 12, a further strip 24 of similar fabric, the edges whereof have been turned under to form hems 25, 26, is caused to overlap concurrently upon a portion of both strips 11 and 12, and is united to the underlying body of strip 10 through strips 11, 12 by means of parallel lines of stitching 27, 28 close to the hemmed edges of strip 24, said lines of stitching defining the inner side of the pockets and concurrently completing the connection of strips 11, 12 with the base strip. It is evident that hemmed edges 25, 26 will be in spaced relation to hemmed edges 22, 23 of strip 10 so that a portion of strips 11, 12 remains exposed to afford access to the pockets formed therein in the manner described.

Figure 5 illustrates a possible practical application of the strap and shows the end portion 29 of a pocket-embodying strap, constructed as described, and the end portion of a cooperating member 30 carrying conventional hooks 31, 32 secured thereto in a suitable manner, for instance by stitching, said hooks being in suitably spaced relation for registering with the series of pockets. Clearly, the pocket-embodying strap will be secured to the garment or other article to which it is applied in such a manner as to present the mouth or free edge 13 of the pockets in the proper position for engagement with the hooks, so that the hooks be entered in any of

the pockets, as it may be desired for adjustment purposes, by causing the nib of the hook to slide underneath free edge 13 of the pockets for engagement of the base-forming surface of the nib with said edge.

In the embodiment illustrated in the fragmentary plan views of Figs. 5a, 5b and 6, and in section in Figures 6a to 6d, wherein these elements common to my first embodiment have been designated by identical reference characters, the base fabric 10 has superimposed thereon a relatively narrower strip 40 spaced inwardly from each side thereof. This strip 40 is folded transversely upon itself to provide a wide pocket formation defined by folds or pleats 13 and 14 forming an elongated infold 15. The fold-embodying strip 40 is secured in pleated condition to the base fabric 10 by lines of stitching 16 and 17 (see Figure 6a), and the longitudinal edges 18 and 19 of the base strip are inturned and stitched along lines 20 and 21 to provide an overlap. (See Figure 6b.) To form the transversely spaced pockets, strip 24, which is narrower than strip 40, is superimposed in spaced relationship to the longitudinal edges of pleated strip 40 and stitched thereto along lines of stitching 27 and 28 (see Figure 6c) to provide the end product strap shown in plan view in Figure 6d.

It will be understood that while I have described and illustrated in the drawing preferred embodiments of the invention, many modifications may be made therein without departing from the spirit of the invention or exceeding the scope of the claims.

I claim:

1. A strap for garments or the like comprising a base strip of fabric, a strip of fabric folded transversely upon itself at spaced intervals longitudinally thereof and superimposed upon said base strip intermediate the side edges thereof, said side edges of the base strip being oppositely folded over upon the longitudinal outer edges of said fold-embodying strip, a further strip of fabric placed centrally of said fold-embodying strip with its side edges spaced inwardly of the folded over side edges of the base strip, to define two series of pockets, and lines of stitching adjacent the side edges of the base strip and adjacent the side edges of the centrally placed strip uniting said edges to the underlying base strip through the fold-embodying narrower strip.

2. A strap for garments or the like comprising a base strip of fabric, two narrower parallel strips of fabric folded transversely upon themselves at spaced intervals longitudinally thereof and superimposed upon said base strip intermediate the side edges thereof, said side edges of the base strip being oppositely folded over upon the longitudinal outer edges of said fold-embodying strips, a further strip of fabric placed centrally of said fold-embodying strips with its side edges in overlapping relation to the inner longitudinal edges of said strips, inwardly of the folded over side edges of the base strip, to define parallel series of pockets and lines of stitching adjacent the side edges of the base strip and adjacent the side edges of the centrally placed strip uniting said edges to the underlying base strip through the fold-embodying narrower strips.

3. A garment strap comprising a base strip of fabric, two narrower parallel strips of fabric superimposed upon said base strip in spaced relation to the side edges of this latter, said narrower strips being folded transversely upon themselves at spaced intervals longitudinally thereof to form

series of pockets, a further strip of fabric located centrally of said narrower strips with its marginal portions overlapping upon the inner longitudinal edges of said narrower strips, the marginal portions of the base strip being oppositely folded over upon the outer longitudinal edges of said narrower strips in spaced relation to the marginal portions of said centrally located strip, the marginal portions of said base strip and the marginal portions of said centrally located strip being united to the underlying surface of the base strip by means of parallel lines of stitching passing through said pocket-forming narrower strips, and said lines of stitching defining the sides of the pockets.

4. A garment strap comprising a base strip of fabric, two narrower parallel strips of fabric superimposed upon said base strip in spaced relation to the side edges thereof, said narrower strips being folded transversely upon themselves at equidistantly spaced intervals longitudinally thereof to form series of pockets and being secured to the base strip by lines of stitching inwardly of the outer longitudinal edge thereof; a further strip of fabric located centrally of said narrower strips with its marginal portions overlapping upon the inner longitudinal edges of said narrower strips, the marginal portions of the base strip being oppositely folded over upon the

- outer longitudinal edges of said narrower strips in spaced relation to the marginal portions of said centrally located strip to expose the pockets formed in said narrower strips, the sides of the
- 5 series of pockets being defined by parallel lines of stitching securing the marginal portions of the base strip and the marginal portions of the centrally located strip to the underlying surface of the base strip through said pocket-forming narrower strips and throughout the length of these latter, said lines of stitching being in closely parallel relation to the aforementioned lines of stitching securing the pocket-forming strips to the base strip.
- 10 15 5. A garment strap comprising a base strip of fabric, two narrower strips of fabric folded transversely upon themselves at spaced intervals longitudinally thereof and secured to the base strip in spaced relation to each other inwardly of the
- 20 side edges of said base strip, a further strip secured to said narrower strips in overlapping relation to the inner longitudinal edges thereof, the marginal portions of the base strip being folded upon the outer edges of said narrower strips and
- 25 secured thereto to expose a portion of the folds formed therein and to cooperate with said further strip in defining series of pockets.

LOUIS M. RABINOWITZ.
